Dec. 1570

Nathan P. Maker, of Pawtucket, R. I.
Letters Patent No. 1570, dated April 29, 1862.

The schedule, referred to in these Letters Patent and making part of the same.

To all whom it may concern:

Be it known that I, N. P. Maker, of Pawtucket, in the County of Providence and State of Rhode Island, have produced a new and ornamental Design for a Crucifix; and I do hereby declare that the following is a full, clear and exact description of the same, reference being had to the accompanying drawings making a part of this specification in which -

Figure 1. represents a perspective view of my design.

Figure 2. is a side elevation of the same.

Figure 3. is a front elevation of the cross alone.

Similar letters of reference in the three views indicate corresponding parts.

The novel points of my crucifix consist in the flaring edges of the several arms composing the cross whereby a comparatively thin cross is made to appear strong and bold; also in the peculiar proportions between said arms and the body of Christ suspended from the same, as will be hereinafter more fully described, whereby the crucifix receives a neat and graceful appearance.

To enable those skilled in the art to fully understand and carry out my design, I will proceed to describe it with reference to the drawing.

The cross A, with the body B of Christ suspended from its arms is intended to be stamped or shaped, by means of dies of gold

2.

or other precious metals and it is therefore desirable to use the least possible quantity of metal and to produce a cross of a stout and bold appearance. This object I have effected by making the edges a. of the cross flaring from the upper surface down towards the lower surface, thereby increasing the apparent thickness of the cross, and making a comparatively thin cross appear heavy and stout.

The proportion existing between the arms of my cross and the body of Christ suspended from the same is as follows: taking the extreme width of one of the arms as the unity, the length of the three arms b. c. d. is equal to $1\frac{1}{3}$, and the length of the arm e. equal to $3\frac{1}{3}$ and taking the length of one of the short arms as the unit, the length of the long arm is equal to $2\frac{1}{2}$. These proportions will be easily understood by referring to Figure 3. of the drawing, which shows the cross separate, and it will be noticed that by using these proportions a cross of a neat and graceful appearance is produced.

The body of Christ suspended from the cross is made in the usual form and shape, being suspended from ten nails passing through the hands, and each foot being fastened by a separate nail, as shown in Figure 1. Its width together with the cloth tied around the body is equal or nearly so to the width of the arm e. and the arm-pits are close over the corners formed between the edges of the arms a. b. and d. of the cross.

The head occupies the centre of the cross, and it is surmounted by a sign f. bearing the usual inscription I.N.R.I. (Jesus Nazarenus Rex Iudearum).

A spherical projection g. bearing a ring is secured to the upper edge of the arm c. for the purpose of suspending the cross from a chain or cord when it is desired to wear the same on the neck.

Having thus fully described my design, what I claim as new and desire to secure by Letters Patent is -

A cross A. with flaring edges a. and having its arms b. c. d. e. proportioned as herein described, with the body B. of Christ suspended from the same and with the inscription f. all as specified.
